(57) **CLAIM**

We claim the ornamental design for a data capture device, as shown and described.

DESCRIPTION

FIG. 1 is a front perspective view of a data capture device;
FIG. 2 is a rear perspective view thereof;
FIG. 3 is a first side view thereof;
FIG. 4 is a second side view thereof;
FIG. 5 is a front view thereof;
FIG. 6 is a rear view thereof;
FIG. 7 is a top view thereof; and
FIG. 8 is a bottom view thereof.
FIG. 9 is a front perspective view of the data capture device, shown without shading rendering lines;
FIG. 10 is a rear perspective view thereof;
FIG. 11 is a first side view thereof;
FIG. 12 is a second side view thereof;
FIG. 13 is a front view thereof;
FIG. 14 is a rear view thereof;
FIG. 15 is a top view thereof; and,
FIG. 16 is a bottom view thereof.
